UNITED STATES PATENT OFFICE

2,563,786

RELIEF VALVE AND SIGNAL FOR FLUID FILTERS

William S. James, Birmingham, Mich., assignor
to Fram Corporation, a corporation of Rhode
Island

Application March 18, 1949, Serial No. 82,162

3 Claims. (Cl. 116—114)

1

This invention relates to a fluid filter, more particularly designed for filtering gasoline. In the filtering of gasoline, it is usual that the filter element be so located that all of the gasoline will pass through the filter in what is usually termed a full flow filter, as distinguished from a by-pass filter. Thus, if such a filter is used in connection with an internal combustion engine and the filtering element becomes clogged by reaching its dirt collecting capacity, no further flow will be had through the filter element. Consequently, the flow of gasoline to the engine will be stopped and it will be necessary to remove the filled filter element in order that the engine may be again started. The removal of the filter for this purpose is not generally known by the user, and consequently it occurs that the engine is out of use until the element may be replaced or removed.

One of the objects of this invention is to provide an arrangement so that should the filter collect sufficient contaminant to become clogged and no longer pass a sufficient amount of fluid for the supply of the engine to which it is attached, there will be a relief or valve means open so that fluid may pass to the engine for the supply of the fuel thereto.

Another object of the invention is to provide some indicating means so that should this flow become clogged and the valve means operate, then the user may be notified of the occurrence and thus replace the element with a fresh one for further use.

Another object of the invention is to provide a signal means which will be readily visible through the transparent bowl which is used in connection with a gasoline filter.

Another object of the invention is to provide an arrangement so that the filter element itself acts as the valve means.

Another object of the invention is to provide a signal which will be released by lifting of the filter element from its seat in acting as the valve means.

Another object of the invention is to provide some indicating device which will be operated by the movement of the filter upon becoming clogged.

With these and other objects in view, the invention consists of certain novel features of construction, as will be more fully described and particularly pointed out in the appended claims.

In the accompanying drawings:

Fig. 1 is a sectional view through the filter showing the filter element on its seat and the

2

indicating means in normal position for operation;

Fig. 2 is a view similar to Fig. 1 illustrating the filter element as raised from its seat acting as a valve and releasing the indicating means;

Fig. 3 is a section on line 3—3 of Fig. 1;

Fig. 4 is a perspective view of the indicating means.

In proceeding with this invention, I provide a head 10 and a bowl which is held together by a nut having screw threaded engagement with a head. Within this bowl there is provided a shell through which entering liquid must pass to reach the exit opening in the head. A filter element is positioned in this shell to seat upon a seat in the shell and close the passage therethrough, except that the fluid will pass through the filtering element. An indicating means such as a U-shaped spring whose arms tend to move toward each other is stretched to engage the seat at diametrically opposite points and is held in this position by a coiled spring urging the filter element toward the seat. Thus, should the element lift from its seat, the spring will be released so that its arms will move toward each other, removing at least one of the arms from the seat, allowing the spring either to hang suspended from one of its arms or to drop completely from position, in either of which cases this change of position will be readily visible, to the user.

With reference to the drawings, 10 designates generally a head which is usually a cast metallic material having an inlet opening 11 which is threaded for connection to a conduit for fluid such as gasoline. There is also provided an exit opening 12 which is similarly threaded for connection to a conduit through which the filtered fluid or gasoline may pass. This exit opening communicates through passages 13 and 14 to the center portion of the head, while the inlet opening 11 communicates through passage 15 to the inner body portion or chamber 16 about the center conduit 14 of the head. A bowl 17, usually of glass, is flanged as at 18 and is held against a soft packing 19 which is urged toward the under surface of the head by a nut 20 having internal threads 21 which engage external threads 22 on the head.

A shell 25 of thin sheet metal has a slotted flange 26 which is held between the gasket 19 and the under surface of the head and extends downwardly into the bowl as shown in the drawings. The lower edge of this shell 25 is flanged inwardly as at 26' so as to provide a surface for supporting a soft gasket 27 which forms a seal-

ing seat. A filter element 30, consisting of a plurality of sheet members rolled into spiral form, is of a size so that its bottom 31 at its outer peripheral edge 32 will engage the soft gasket 27 and by reason of a coiled spring 33 will be forced against this seat 27 to provide a fluid tight fit to prevent passage of fluid into the shell except that which passes through the filter element 30. Spring 33, while engaging on the top of the filter element 30 at one end, also engages a cup 34 which has a downwardly sloping surface and a flange 35 to rest upon the top of the shell flange 26. This flange 35 is provided with a plurality of slots which register with slots in the flange 26 so as to provide for the liquid passing into the bowl as shown by arrow 36. A soft gasket 37 also serves to seal the cup 34 at its upper edge from the entrance flow of liquid into the device.

An indicator designated generally 40 (Fig. 4) is provided with a pair of arms 41 connected by body 42 with the arms flattened as at 43 at each end. This U-shaped member is spread so that instead of the arms being in the position shown in Fig. 4 they will be stretched to the open position shown in Fig. 1 and with the arms so positioned under tension with the parts 43 resting on the soft seat 27 and engaged by the filter element 30 the indicator 40 will be held in place as shown in Fig. 1 by friction between seat 27 and the bottom 31 of the filter element 30 under the action of the spring 33.

In operation, the fluid will pass inwardly through the opening 11 down through the slots 36 into the bowl 17 and upwardly into the shell 25 and through the filter 30 and thence out through the conduits 14, 13, and 12. Should the filter element 30 become clogged, the strength of the spring 33 is such that the filter element will lift from its seat 27 to permit the passage of fluid around the outer surface of the filter element 30 which is spaced from its shell 25 and at the same time the indicator 40 being relieved of pressure upon its ends 43 will permit the arms 41 to spring toward each other and become displaced from the seat 27, either hanging by one of its arms or dropping completely from position onto the bottom of the bowl. The bowl being transparent, the same will be readily visible so that one looking at the filter will know that the element has become clogged and is only permitting operation by moving to a by-pass position. Thus, if the filter has been left too long or the contaminant has been unduly heavy, a positive indication is shown that a change should be made.

I claim:

1. In a fluid filter, a head provided with means for the entrance and exit of a fluid to be filtered, a transparent bowl, means to detachably secure said bowl to said head, means providing a passage

from the entrance through the bowl to the exit, means providing a shoulder along said passage to form a sealing seat facing the outlet side of the passage, a filtering element in said passage, resilient means urging said element toward the inlet side of the passage against said seat to provide a seal but of a strength to permit said element to raise off said seat should the element become clogged, a U-shaped member held on said seat by said filter element when in seated position but released when said element is raised from said seat.

2. In a liquid filter as in claim 1, wherein said U-shaped member has its arms under tension to move toward each other when the filter element is released by its being raised from the seat.

3. In a fluid filter, a head provided with means for the entrance and exit of fluid to be filtered, a transparent bowl, means to detachably secure said bowl to said head, means providing a passage from the entrance through the bowl to the exit, means providing a shoulder along said passage to form a sealing seat facing the outlet side of the passage, a filtering element in said passage, resilient means urging said element toward the inlet side of the passage against said seat to provide a seal but of a strength to permit said element to raise off of said seat should the element become clogged, an indicator, means to mount a portion of said indicator between said sealing seat and part of the element supported by said seat and with another portion of the indicator depending from said seat, whereby said indicator is released in response to the movement of said filtering element from said seat and is dislodged from the seat by gravity.
